CLAIM

I claim the ornamental design for a sunglasses lanyard, as shown and described.

DESCRIPTION

FIG. 1 is an environmental perspective view of a sunglasses lanyard showing my new design and showing a pair of sunglasses in phantom; the sunglasses forming no part of the claimed design;

FIG. 2 is a first view of the sunglasses lanyard laid flat;

FIG. 3 is a second view of the sunglasses lanyard laid flat; and,

FIG. 4 is an end view of the sunglasses lanyard.
